W. F. SCHMIDT

TOY PISTOL

Filed July 1, 1922

By Raymond A. Parker

Attorney

Patented Dec. 4, 1923.

UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF DELAWARE.

TOY PISTOL.

Application filed July 1, 1922. Serial No. 572,254.

To all whom it may concern:

Be it known that I, WILLIAM F. SCHMIDT, citizen of the United States, residing at Wyandotte, county of Wayne, State of Michigan, have invented a certain new and useful Improvement in Toy Pistols, and declare the following to be a full, clear, and exact description of the same, such as will enable others skilled in the art to which it pertains to make and use the same, reference being had to the accompanying drawings, which form a part of this specification.

My invention relates to toy pistols and an object of my improvements is to provide 15 an improved construction that is cheap to make and convenient to assemble. I accomplish this object in the device illustrated in the accompanying drawings, in which:

20 Figure 1 is a side elevation of a pistol embodying my invention.

Fig. 2 is a rear elevation of the same.

Fig. 3 is a side elevation with the portion of the stock, or handle, that is toward 25 the observer, removed.

Fig. 4 is a section on the line IV—IV of Fig. 1.

Fig. 5 is a detail section in the plane indicated by the line V—V, Fig. 3.

30 Fig. 6 is a detail section on the line VI—VI, Fig. 1.

Fig. 7 is a detail section on the line VII—VII, Fig. 1.

Fig. 8 is an elevation showing the upper 35 and rear portion of the trigger piece, its pivot pin, and a section of the spring-retracting rod.

40 *a* indicates a stock for grasping and holding the barrel and providing the handle. This stock is made of two similar and corresponding parts *a*², *a*³, each of which parts is bent into a semi-cylindrical form at the top so that when the parts are put together they form an approximately cylindrical portion in which the barrel is 45 grasped and held as described below. The part *a*³ of the stock is punched out forming holes *a*⁴, *a*⁵, with pins *a*⁶ struck up therefrom and extending inwardly. The pins *a*⁶ 50 engage through apertures in the sunken portion *a*⁷, *a*⁸ of the part *a*² and are bent over at *a*⁹, *a*¹⁰ to clamp the part *a*² to the part *a*³. The part *a*³ is again punched to form an aperture *a*⁸ with an inwardly-projecting pin *a*⁹ turned up from the part *a*³,

which pin consists of material struck out of said part to leave the aperture *a*⁸.

*a*¹⁰, *a*¹⁰, *a*¹⁰, *a*¹⁰ are indentations in the side of the cylindrical portions of the stock part *a*², *a*³, which form inwardly-extending 60 lugs to engage in apertures *b*³ in the barrel *b* to hold said barrel in place, as herein-after described.

*a*¹¹, *a*¹¹ are apertures formed opposite each other in the parts *a*², *a*³ of the stock 65 at a position to receive the lateral lugs of the spring-retaining piece, as herein-after described. *a*¹² is a slot formed along the upper portion of the cylindrical portion of the stock toward the rear thereof, for the 70 purpose herein-after described.

b is the barrel which is a cylindrical tube formed by rolling sheet metal and open at both ends. This barrel has slots *b*³, *b*³ formed in its sides into which the lugs *a*¹⁰ 75 of the stock engage to hold the barrel in place.

c is a spring-retracting rod turned upwardly at *c*² at its rear end and provided with a piston *d* at its forward end, which 80 piston is adapted to fit and reciprocate in the barrel *b*.

f is a spring-holding part having lateral lugs *f*², *f*². The part *f* is passed over the 85 rod *c*.

e is a helical spring, one end of which engages against the piston *b* and the other end against the retaining part *f*.

*c*³ is a notch in the under side of the rod *c* 90 adapted to engage over the edge of the aperture through the retaining part *f* to hold the spring *e* in its retracted position until released by the trigger.

g is the trigger piece pivoted upon the pin *a*⁹ and provided with an upwardly-extending finger *g*² at its upper end and turned over at *g*³, as shown most distinctly in Fig. 8, so as to enable it to contact the spring-retracting rod *c* to displace the same to release the spring.

95 The method of assembling the above parts is as follows: The barrel *b* having the spring *e* and piston *d* therein is placed between the parts *a*², *a*³ of the stock with the up-turned end of the spring-retracting rod *c* extending through the slot *a*¹². The parts *a*², *a*³ are forced together, engaging the lugs *a*¹⁰ in the apertures *b*³ of the barrel, the pins *a*⁶, *a*⁶ extending through slots in the depressions *a*⁷, *a*⁸ of the part *a*². These pins 105 *a*⁹, *a*⁹ of the part *a*³.

are then turned over at a^6 , a^8 to bind the two parts together.

In putting the parts a^2 , a^3 together as above described, the spring-retaining piece f has its lugs engaged in the apertures a^{11} , a^{11} of the stock and the trigger piece g is placed upon the pin a^9 , its finger g^2 extending upwardly and engaging between the rear end of the spring e and the spring-retaining piece f . Thus said spring acts to force the upper part of the trigger piece g backward and its upper and back end downwardly.

To set the spring, the operator takes hold of the part c^2 of the rod c and draws backward and downward thereon, thus drawing the piston d backwards, compressing the spring e and engaging the notch c^3 over the edge of the aperture of the retaining piece f .

This brings the rod c directly above the rear end of the trigger piece g , as shown in Fig. 8. To release the spring, the trigger piece g is drawn upon, oscillating it around the pin a^9 , carrying its upper portion g^3 upward, thereby pushing the rod c out of engagement with the spring-retaining piece f and thus releasing the spring.

It will be observed that the major parts of the above construction are made of sheet metal, which may be readily formed by the usual operation—that the engaging parts are struck out of the metal and do not require separate pieces, and that the single spring acts at once as the main spring and as the trigger spring.

What I claim is:

1. In an apparatus of the kind described, a sheet metal stock having a lug bent up from the material thereof, and a trigger piece pivotally engaging upon said lug.

2. In an apparatus of the kind described, a stock, a spring, a spring-retaining part in said stock, a spring-retracting rod extending through said spring-retaining part and

45 adapted to engage over the edge thereof in its retracted position, and a trigger piece having a lug engaging between said spring-

retaining piece and the adjacent end of the spring and adapted to displace said rod from its engagement with the spring-retaining piece.

3. In a construction of the kind described, two sheet metal parts adapted to be bound together to form the stock, a pin a^9 struck up from the material of which one of said parts consists and extending inwardly, and a trigger piece g pivotally engaging upon said pin.

4. In a construction of the kind described, a barrel b having a spring e therein, said barrel being open at one end, a rod c extending through said spring and engaging one end thereof, a piece f upon said rod engaging against the other end of said spring, said piece having lugs f^2 extending laterally therefrom, parts a^2 , a^3 adapted to be bound together to form the stock and having apertures a^{11} , a^{11} , therein, said lugs engaging through said apertures and said stock engaging said barrel when said parts are bound together to form the stock, and a trigger piece g pivoted in said stock and engaging between said spring and the retaining piece f .

5. In a construction of the kind described, a barrel b having a spring e therein, said barrel being open at one end, a rod c extending through said spring and engaging one end thereof, a piece f upon said rod engaging against the other end of said spring, said piece having lugs f^2 extending laterally therefrom, parts a^2 , a^3 adapted to be bound together to form the stock and having apertures a^{11} , a^{11} therein, said lugs engaging through said apertures and said stock engaging said barrel when said parts are bound together to form the stock, and a trigger piece g pivoted in said stock and engaging between said spring and the retaining piece f , and lugs a^{10} engaging said barrel.

In testimony whereof, I sign this specification.

WILLIAM F. SCHMIDT.
